UNITED STATES PATENT OFFICE

CHARLES ALGERNON PARSONS AND JESSEL ROSEN, OF NEWCASTLE-UPON-TYNE, ENGLAND, SAID ROSEN ASSIGNOR TO SAID PARSONS; KATHARINE PARSONS, VINCENT THOMPSON AND FREDERICK GORDON HAY BEDFORD, LEGAL REPRESENTATIVES OF SAID CHARLES ALGERNON PARSONS, DECEASED

ELECTRICAL MACHINERY

Application filed July 3, 1928, Serial No. 290,225, and in Great Britain July 5, 1927.

The invention relates to the ventilation of dynamo-electric machinery, transformers and the like.

In modern practice it has become common, particularly in the case of high-speed alternators of large output, to employ the closed-circuit system of ventilation, in which the air after its passage through the alternator is led to suitable coolers, the same air being circulated round the circuit continuously.

In such high-power machines the ducts involved are expensive to manufacture and install on account of their large dimensions, while great difficulty is experienced in finding room for their accommodation.

The main object of the present invention is to overcome such difficulties.

With such an object:—

The present invention consists in a ventilation system of the kind indicated in which the gaseous cooling medium flows in series through a plurality of stages of the dynamo-electric machine, transformer or the like and is subjected to intermediate cooling between such stages.

Referring to the accompanying drawings:—

Figure 1 shows a longitudinal view for the most part in section of an alternator cooled in accordance with the present invention,

Figure 2 as regards its left-hand half being an end view of the alternator shown in Figure 1 and as regards its right-hand half a cross-section on the line 2—2 of Figure 1;

Figure 3 shows in longitudinal section to a larger scale a modified form of baffle arrangement,

Figure 4 being a part cross section on the line 4—4 of Figure 3, and

Figure 5 a part cross section on the line 5—5 of Figure 3; finally

Figure 6 shows a modified form of the invention in cross section.

The same reference symbols are used in the different figures to denote corresponding parts.

The arrows in Figure 1 show the general direction of the circulating air.

In carrying the invention into effect according to the illustrative form shown in

the figures as applied to an alternator with a stationary armature, the coolers, A¹ to A⁵, are arranged in the foundation of the machine and the cooled air issuing therefrom is led by an external inlet passage, B, of which an end shield, C, of the alternator may form one wall, to an annular duct, D, whence a fan, F, mounted on the rotor shaft, G, forces it into the space between the end shield, C, and end wall, H, of the dynamo. After cooling the armature end windings, J, arranged in this space, the cooling air passes through holes, K, in the end wall into the first, L¹, of a series of axially-disposed annular ducts, L¹ to L⁵, which vary in cross-section to suit the build of the machine and encircle corresponding zones or stages, M¹ to M⁵, of armature core sections. These sections throughout the machine are provided with passages or ducts, N¹ to N⁵, running radially outwards from the air gap, O, and also with axial connecting ducts, P¹ to P⁵, so that the cooling air described above is joined in the first annular duct, L¹, by other cooling air which has flowed radially outwards through the ducts, N¹. The two streams of air thus united pass downwardly into a cooler section, A¹, running across the base or foundation of the machine, this cooler being of any standard tube construction provided with the usual water box or boxes, Q, and so forth.

The first cooler section, A¹, extends axially over the length of the first and second annular ducts, L¹ and L², so that the cooled air from the duct, L¹, forced to traverse the cooler by suitable baffles, S¹, then passes into the second annular duct, L², and radially inwards through the passages, N², between the core sections, whence it passes by way of the axial passages, P², and air gap to the third annular duct, L³, the third and fourth ducts, L³ and L⁴ corresponding to the first and second and being likewise provided with a cooler section, A², with baffle, S², arranged in the foundation of the machine.

Finally, in the particular example of the invention under description, the cooled air passes from the second cooler section, A², to the fifth and last stage, M⁵, of core sections and thence by way of the corresponding an-

nular duct, L^5 , to a final cooler section, A^3 , arranged alongside those above described. From this cooler section, the cooled air passes by way of the inlet passage, B , described above, to repeat the circuit.

The cooler should in all cases be arranged so as to prevent any surface condensation being carried on to the windings, while known precautions such as drying make-up air, using a dry agent in the system or other similar means, can be taken as required.

Circumferential baffles, such as R , projecting from the core sections, R^1 , R^2 , lying respectively between the annular ducts, L^1 , L^2 , and L^3 , L^4 , may be provided to prevent air passing along the air gap, O , without flowing through the coolers.

According to a preferred modification as shown in Figures 3, 4 and 5, however, the baffle device consists of a tube, T , preferably of a non-metallic material, such as presspahn or bakelite, inserted in the stator bore, a small clearance, U , being left between the tube, T , and the rotor, G . The tube, T , takes the form of a solid annulus as indicated in Figure 3 at T^1 , in way of the core section, R^1 , and similarly in way of the core section, R^2 , or wherever else baffles are required, but at other points of its length, the tube, T , is provided with axial holes, T^2 , and radial perforations, T^3 , spaced to register with the ducts, N , between the core sections, the air taking the same course through the various ducts as described above with reference to Figure 1.

As shown in Figure 6, the longitudinal perforations may be replaced by grooves, T^4 , running longitudinally along the outer surface of the tube, T , these grooves preferably conforming in breadth with the configuration of the core sections, M ; in some cases, the bottom walls of the grooves may be perforated as shown at T^5 .

Such a tubular form of baffle is strong and readily secured in place in the stator bore; moreover, owing to its shape and absence of projections, the rotor can be slid in or out longitudinally without damage to itself, to the baffle tube or to the stator.

Preferably, as described above, the circulation is effected by means of a fan attached as described to the rotor shaft and disposed in the space between the end shield and the end wall of the dynamo but separately driven fans may be employed, or alternatively fans coupled to the rotor shaft, while in addition any suitable gas may be circulated instead of air.

By virtue of the present invention instead of circulating, for example 60,000 cubic feet of air per minute in an alternator with the methods of cooling hitherto employed and with a total pressure drop of 5 inches of water, a much less volume of air amounting to, say 10,000 cubic feet per minute with a consequent large decrease in the size of the

ducts required, may be employed with a total pressure drop of 22 inches of water, the power required for driving the air through the system being thus somewhat lower in comparable cases.

Owing to the reduction in size of the large external ducts, their cost and also the cost of the foundations is reduced in the form of the invention described above.

Although one form of the invention has been described in detail, it will be evident that its scope is wide enough to include many variations as regards, for example, the disposition of the actual cooling passages and coolers, so long as the ventilating air or the like is subjected to intermediate cooling on its passage through the machine.

We claim:

1. A dynamo-electric machine having co-axial stator and rotor members separated by an air gap, a tube disposed in said gap, said tube being co-axial with the axis of rotation of the machine and having ducts therein, and means for circulating a cooling medium in a given path through said machine, the given path including said ducts.

2. A dynamo-electric machine having co-axial stator and rotor members separated by an air gap, said stator having a plurality of juxtaposed core sections with ducts therebetween, a tube co-axial with the axis of said machine and having ducts in operative juxtaposition with the ducts of the core sections, and means for circulating a cooling medium through said machine in a given path including the ducts between the sections and the tube ducts.

3. A dynamo-electric machine having co-axial stator and rotor members separated by an air gap, said stator having a plurality of juxtaposed core sections with radial ducts therebetween, a tube co-axial with the axis of the machine and disposed in the air gap, said tube having longitudinally disposed ducts in operative association with the radial ducts, said tube having ductless portions forming baffles between the sections, and means for circulating a cooling medium through the machine in a given path including the ducts between the sections and the tube ducts.

4. Ventilating system for a dynamo-electric machine, comprising a stator having a series of core sections and radial passages therebetween, a rotor member disposed within said stator with an intervening air gap, a plurality of juxtaposed ducts surrounding said core sections, each duct being in communication with a plurality of said radial passages, intercoolers connecting said ducts, directing means disposed in said air gap and means for circulating a cooling medium through said passages, said ducts and said intercoolers.

5. Ventilating system for a dynamo-elec-

tric machine as claimed in claim 4, in which said intercoolers connected with said juxtaposed ducts are also juxtaposed and are secured to and aligned along the base of said 5 dynamo-electric machine.

6. Ventilating system for a dynamo-electric machine, comprising a stator having a series of core sections and radial passages therebetween, a rotor member disposed within 10 said stator with an intervening air gap, a plurality of juxtaposed ducts surrounding said core sections and in communication with said passages, intercoolers connecting said ducts, said intercoolers being juxtaposed and 15 embodied in a single structure, directing means disposed in said air gap and means for circulating a cooling medium through said passages, said ducts and said intercoolers.

7. A dynamo-electric machine comprising 20 a stator having a series of juxtaposed core sections and passages connecting said sections, a rotor member disposed within said stator with an intervening air gap, in combination with means for circulating a cooling medium 25 through said sections in series stages, said circulating means including directing means disposed in said air gap, and cooling means for said medium operatively disposed in relation to said passages at an intermediate point 30 of the flow through said series of sections, said cooling means forming a unit embodied in the structure of the dynamo-electric machine and common to a plurality of said stages.

8. A dynamo-electric machine comprising 35 a stator having a series of juxtaposed core sections and passages connecting said sections and a rotor member disposed within said stator with an intervening air gap, means defining a series path through the 40 core sections, said defining means including directing means disposed in said air gap, means for circulating a cooling medium through said path, and cooling means in said 45 path between sections, the cooling medium passing through the cooling means of alternate sections in different directions, said cooling means forming a unit embodied in the structure of the dynamo-electric machine and 50 common to a plurality of said sections.

9. A dynamo-electric machine comprising 55 a stator having a series of juxtaposed core sections and passages exterior to the core sections connecting said sections, and a rotor member disposed within said stator with an intervening air gap, directing means disposed in said air gap, means for circulating a cooling medium through said sections and 60 passages in series as determined by said directing means in said air gap, the core sections having radial ducts for conducting the cooling medium in parallel, and cooling means for said medium operatively disposed in relation to said passages at an intermediate point of the flow through said series 65

of sections, said cooling means forming a unit embodied in the structure of the dynamo-electric machine and common to a plurality of said sections.

10. A dynamo-electric machine having co- 70 axial stator and rotor members separated by an air gap, means for circulating a cooling medium in a given path through said machine and air gap, said means including an annulus in said air gap provided with air 75 passages and baffles for directing the cooling medium through the parts of the machine to be cooled.

11. A dynamo-electric machine having co- 80 axial stator and rotor members with an intervening air gap, one of said members having a series of core sections and radial passages therebetween, a plurality of juxtaposed ducts surrounding said core sections, each duct being in communication with a plurality of said radial passages, and means for circulating a gaseous cooling medium in a given path through said passages and ducts, said circulating means including means disposed in said air gap between said pluralities 85 of radial passages for directing the cooling medium through the parts of the machine to be cooled.

12. A dynamo-electric machine having co- 90 axial stator and rotor members with an intervening air gap, one of said members having a series of core sections and groups of radial passages therebetween, and means for circulating a gaseous cooling medium alternately inwards and outwards through said 95 groups of radial passages, said circulating means including directing means disposed in said air gap.

In testimony whereof we have signed our 100 names to this specification.
